THEODORE RAY MINERT, OF ST. PAUL, MINNESOTA, ASSIGNOR TO CHIPPEWA FOUNDRY & MACHINE COMPANY, OF CHIPPEWA FALLS, WISCONSIN, A CORPORATION OF WISCONSIN.

PUMP-OPERATING MECHANISM.

1,200,214.

Specification of Letters Patent.

Patented Oct. 3, 1916.

Application filed June 4, 1915. Serial No. 32,205.

To all whom it may concern:

Be it known that I, THEODORE RAY MINERT, a citizen of the United States, residing at St. Paul, in the county of Ramsey 5 and State of Minnesota, have invented a new and useful Improvement in Pump-Operating Mechanism, of which the following is a specification.

This invention relates to improvements in 10 pump operating mechanism and more particularly is adapted for use in connection with deep well pumps for pumping a steady stream of water or other liquid and with air compressors.

15 An object of this invention is to arrange the pump operating mechanism symmetrically about a center line, whereby lateral forces are evenly distributed, friction and wear of the working parts are reduced to a 20 minimum, and the parts arranged in compact form.

25 A further object is to combine into a single structure a plurality of devices of the character stated, wherein a double acting pump can be operated by a minimum amount of power and wherein side thrust is materially reduced, thus obviating noise and clatter as with structures now in common use. As a 30 result of these features, a smoothly operating mechanism is produced, which is comparatively simple and inexpensive in construction, admitting of application to pumps of various kinds for raising water and other liquids and compressing air with a minimum 35 amount of power, and in a constant steady stream or supply.

With the above objects and others which will be apparent to those familiar with the art, to which this invention relates, my invention 40 comprises the features of construction and combinations of parts hereinafter more particularly described and claimed.

In the drawings, Figure 1 is a front elevation of my invention; Fig. 2 is a side elevation partly in section; Fig. 3 is a section of a detail taken on the line X-X of Fig. 2; Fig. 4 is another section of a detail taken on the line Y-Y, of Fig. 2, and Fig. 5 is a view illustrating diagrammatically 50 the principle of operation of my invention.

My invention is particularly although not exclusively adapted for use in operating double acting pumps employing two reciprocating elements adapted to be driven to

raise liquid in a steady stream. The pump to which the invention is applicable is of ordinary construction, and not therefore illustrated in the drawing, it being sufficient to indicate the reciprocating connections by which my improved apparatus is connected with the pump.

I employ three power units indicated by A, B and C upon the drawings, said units being substantially similar in construction, and operated by a single drive shaft such as 2, 65 which is journaled for illustration in a suitable supporting frame D. The unit A is adapted to be connected with the stem or inside shaft 3 leading downwardly and adapted to be connected with one of the 70 pump pistons, while the units B and C are connected to the tube or outside shaft 4 to reciprocate the same, said outside shaft being connected to the other pump piston and slidably supporting the stem 3 therein. To 75 briefly describe the features in each of said units, reference will first be made to the diagrammatic view illustrated in Fig. 5, and the main elements therein pointed out and the mode of operation thereof explained so 80 as to lay proper foundation for a description of the details of construction to follow.

The single form of apparatus consists briefly of the shaft 2 journaled in suitable fixed bearings such as 3 carried by the frame 85 D, said shaft being driven by any suitable source of power, the drawings illustrating a pulley 1 for revolving the shaft, which may be driven by a belt not illustrated. Mounted upon the shaft 2 are pinions 5 or driving 90 gear wheels, the teeth of which mesh with the teeth of a crank gear wheel 6. This crank gear wheel is journaled upon an eccentric pivotal connection 7 carried by the lower end of a hanger 8, said hanger being 95 pivotally suspended from a shaft 9 at its upper end and said shaft being carried by the upper end of the frame D. Pivotally mounted upon the drive shaft 2 and formed with a strap 10 encircling a hub 11 on a 100 side of the crank gear wheel is a link 12, whereby as the shaft 2 turns the crank gear wheel 6 is revolved evenly, the teeth of said crank gear being held in mesh with the teeth of the drive gear 5 by the coöperating 105 hanger and link. Said hanger and link are so arranged as to cause the crank gear to turn orbitally about the axis of the drive

shaft, and impart an up and down movement to the link and crank gear.

Arranged below the mechanism described is a reciprocating member such as 3 or 4 out of alinement with said hanger support, said reciprocating element 3 being pivotally connected to one end of a pitman 14, the opposite end of said pitman having eccentric pivotal connection at 15 with said crank gear. 10 The latter connection is diametrically opposite to the pivotal connection between the hanger and said crank gear. As a result reciprocating motion is imparted to the pump element such as 3 or 4, by the crank gear. 15 The path which the pivotal connection 15 describes is in an elliptical line, the long axis of the ellipse being up and down and in substantial alinement with the reciprocating movement of the reciprocating element such as 3 or 4. The ellipse referred to is irregular, one side thereof being shorter than the other, caused by the swinging movement of the link, whereby a quicker downward thrust is imparted by the crank gear to the pump element such as 3 or 4 than the upstroke or return movement. This is an advantage because a more direct pumping stroke is imparted to the reciprocating element such as 3 or 4, with less side thrust and 20 when more than one of said units is employed for the purpose of operating a plurality of pumps, the strokes of the reciprocating elements overlap each other, causing a continuous even stream to issue from the pump without any noticeable pulsating action. By arranging the hanger support out of alinement with the reciprocating pumping elements 3 and 4, said pumping elements can be disconnected and removed without 25 dismantling the entire apparatus. The mechanism described is only a skeleton outline of the features and operation of my invention, the invention being susceptible of an assemblage of a plurality of said units, 30 the various details of construction of which will be hereinafter more particularly described.

As before stated, my invention includes in addition to the simplest form of construction described, a plurality of pump operating devices symmetrically arranged, so as to compensate lateral thrust, which usually tends to produce friction, jar, irregularity and noise, rendering the apparatus 35 inefficient.

The frame D as illustrated is composed of a suitable base 20, upon which is mounted two end members 20' and 21, across the upper portions of which is secured a stationary supporting shaft 22. Disposed horizontally across the space between the end members 20' and 21 is a horizontal brace or buttress 23 and depending from and secured to the base 20 is a yoke frame 24, the latter supporting a guide bearing 25, in

which the tubular pump shaft 4 slides. The upper end of the inner pump shaft 3 is secured by a coupling 26 to an inner cross head 27, which is mounted to slide vertically in a pair of oppositely disposed guides 28 and 29, said guides being rigidly secured by their lower ends to the base 20 and by their upper ends to the buttress 23. Pivotally attached to the inner cross head 27 is a pitman 30 corresponding to the pitman 14, the upper end of said pitman being secured by an eccentric pivotal connection 31 to the inner adjacent faces of a pair of crank gears 32 and 33 placed side by side and spaced apart. These crank gears 32 and 33 have journaled upon their outermost sides, a pair of hangers 36 and 37, by eccentric pivotal connections 34 and 35, which are diametrically opposite the pivotal connection 31, between the pitman 30 and said crank gears. Said hangers are suspended by their upper ends from the supporting shaft 22. The crank gears 32 and 33 are formed on their outermost sides with projecting hubs or shoulders 38 and 39, and upon these hubs are freely journaled straps 40 and 41, said straps being rigidly coupled together by a spacing bar 43. The straps 40 and 41 are respectively carried by or formed upon links 44 and 45, each corresponding with the link element 12. These links 44 and 45 are pivotally mounted upon the single drive shaft 2, whereby the crank gears are free to swing up and down as they turn in the straps on the links and as they revolve eccentrically about their journal connections with said hangers. In this manner the parts of the apparatus which convert the revolving motion of the drive shaft into the reciprocating motion of a pump shaft are symmetrically arranged about a vertical center line passing downwardly through the pivot point of the hanger's support.

Units B and C are each similar in construction to the element A, excepting that a different mechanism is employed for connecting the pitmen thereof to the outside reciprocating pumping element 4 as will be hereinafter described. A detail description of each of these units is not therefore necessary, the description of the unit A sufficing. However it will be noted that the units B and C are driven by the same drive shaft 2 which operates the unit A, and that the position of the pitmen of the units B and C is such that the extreme end of the upstroke of the inside pump shaft 3 occurs simultaneously near the extreme end of the down stroke of the outside pump shaft 4 and that said strokes overlap. The units B and C are positioned evenly on the opposite sides of the unit A, said unit A occupying a position midway between them. The pitmen 50 and 51 respectively of the units B and C are rigidly coupled to an outside cross-head 52, 130

said cross-head being slidably mounted on the outer surfaces of the guide members 28 and 29 and caused to be moved vertically thereby. The cross-head 52 is secured to the 5 upper end of the outside pump shaft 4 by a plurality of vertical rods 53 and a coupling 54 secured to the member 4, all of said parts being symmetrically arranged so as to minimize all side thrust. By employing inside 10 and outside cross-heads the parts are arranged in more compact form and the height of the entire structure reduced.

In operation the drive shaft 2 is revolved continuously at even surface speed, and the 15 revolving motion thereof is converted into the reciprocating motion of the pump actuating shafts 3 and 4, said shafts being reciprocated upwardly successively at even intervals and returning downwardly by quick 20 return strokes. The distribution of all of the parts of the apparatus being symmetrically arranged reduces friction, lateral thrust and noise to a minimum, thus converting rotary motion into reciprocating motion by 25 smoothly operating working parts. As a result an even steady stream of water or other liquid or air is delivered by the pumping apparatus. Obviously the operation of the mechanism can be reversed and a quick up 30 stroke and slow return stroke of the pumping mechanism produced.

In accordance with the patent statutes I have described the principles of operation of my invention, together with the apparatus 35 which I now consider to represent the best embodiment thereof, but I desire to have it understood that the construction shown is only illustrative, and that the invention can be carried out by other means and applied 40 to uses other than those above set forth within the scope of the following claims.

Having described my invention, what I claim as new and desire to protect by Letters Patent is:

45 1. Pumping apparatus, comprising, in combination, a pair of adjacent co-axially arranged pump shafts arranged to reciprocate successively, a revolute driving element journaled on a fixed support, a plurality of 50 crank members, pitmen connected to said pump shafts and by eccentric pivotal connections to said crank elements arranged to reciprocate said pump shafts successively, means carried by said revolute shaft for 55 revolving said crank elements, links pivoted substantially on the axis of said revolute driving member in the free portions of which said crank elements are journaled, and hangers hung from a fixed support and 60 having eccentric pivotal connection with said crank elements substantially diametrically opposite said pivotal connections to said pitmen.

65 2. Pumping apparatus, comprising, in combination, a pair of adjacent pump shafts

arranged to reciprocate successively, a revolute driving element journaled on a fixed support, a plurality of crank elements, links pivoted substantially on the axis of said driving element in the free portions of which 70 said crank elements are journaled, hangers hung from a fixed support and having eccentric pivotal connection with said crank elements, slidable cross-heads arranged to travel one within the other and to which 75 said pump shafts are respectively attached, and pitmen connected to said cross-heads and to said crank elements by eccentric pivotal connections substantially diametrically opposite said pivotal connections to said 80 hangers.

3. Pumping apparatus, comprising, in combination, a pair of pump shafts to be reciprocated successively, a revolute driving element journaled on a fixed support, a plurality of crank gears, pitmen connected to 85 said pump shafts and by eccentric pivotal connections to said crank gears arranged to reciprocate said pump shafts successively, a gear connection carried by said revolute 90 shaft having teeth in mesh with the teeth of said crank gears, links pivoted substantially on the axis of said revolute shaft and in the free portions of which said crank gears are journaled, and hangers hung from 95 a fixed support and having eccentric pivotal connections with said crank gears arranged substantially diametrically opposite said pivotal connections to said pitmen.

4. Pumping apparatus, comprising, in 100 combination, a pump shaft to be reciprocated, a revolute shaft, the motion thereof to be converted into the reciprocating motion of said pump shaft, a gear wheel mounted on said revolute shaft, a crank gear having teeth in mesh with the teeth of said gear 105 carried by said revolute shaft, a link pivoted on said revolute shaft and in the free end of which said crank gear is journaled, a fixed support in which said 110 revolute shaft is journaled, a hanger hung from said support and having an eccentric pivotal connection with said crank gear, and a pitman connected with said pump shaft and having an eccentric pivotal connection with said crank gear disposed substantially diametrically opposite the pivotal connection between said hanger and crank gear, said pump shaft being arranged out of alinement with said hanger support for 115 120 the purposes specified.

5. Pump apparatus, comprising, in combination, a pump shaft arranged to reciprocate, a cross-head slidably supported and carried by said shaft, a revolute driving 125 element journaled on a fixed support, a pair of driving gears carried by said revolute element, a pair of links pivoted upon said revolute element, a pair of crank gears journaled in the free ends of said links and 130

arranged with innermost adjacent sides spaced apart, a pitman secured to the adjacent faces of said crank elements by an eccentric pivotal connection and to said cross-head, and hanger means suspended from a fixed support and having two eccentric pivotal connections with the outermost sides of

10 said crank elements disposed substantially diametrically opposite said pivotal connections to said links.

In testimony whereof, I have signed my name to this specification.

THEODORE RAY MINERT.
